HAIR WAVING DEVICE

Virginia S. Graham, Los Angeles, Calif.

Application June 15, 1943, Serial No. 490,867

10 Claims. (Cl. 132—38)

This invention relates to hair waving devices. It is an important object of this invention to provide such a device which may be readily applied by the user to her own head.

It is another object of this invention to provide such a device which will allow free circulation of air about the hair being waved.

It is still another object of this invention to provide such a device wherein the user's head is protected from contact with sharp projections or teeth on the device.

It is still another object of this invention to provide such a device having improved clamp means.

This invention possesses many other advantages and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawing:

Figure 1 is a front elevation showing the device in use, as seen from a position somewhat above the head;

Figure 2 is a side elevation of the device, partly in section;

Figure 3 is a plan view;

Figure 4 is a cross section taken on line 4—4 of Figure 2; and

Figure 5 is a detail section taken on line 5—5 of Figure 2.

Referring to the drawing, the device comprises a pair of arcuate corrugated members 10 and 11 adapted to rest on the head as shown in Figure 1 and to have the strands of hair which it is desired to wave interposed between the members as indicated by 12, when the members are nested. The member 10 is formed with a plurality of sharp peaks or ridges 13 separated by rounded valleys or depressions 14, these ridges and depressions 13 and 14 extending longitudinally of the member 10. The upper member 11 has corresponding ridges 15 and valleys 16, the ridges 15 being rounded and the depressions 16 being sharp, for cooperating with the ridges 13 and valleys 14 of the member 10. The means 17 and 18 are provided for maintaining the members 10 and 11 in vertical spaced relationship whereby the ridges 13 and 15 and the valleys 14 and 16 cooperate to

form a channel 19 for the reception of the hair strands 12. It will be apparent that the channel 19 will curve or wave the hair therein in a generally vertical direction.

5 To impart a more pleasing appearance to the hair, it is desirable that it be also waved in a generally horizontal direction. For this purpose, the means 17 and 18 which serve to space the members 10 and 11 may each comprise a row of teeth as 21 and 22 (Figure 2) resembling the teeth of a comb and adapted to have the hair 12 passed between. It will be apparent that with the confined hair between the teeth 21 and 22 of adjacent rows, relative longitudinal movement between the members 10 and 11 will impart a horizontal wave to the hair in addition to the vertical wave imparted by the configuration of the channel. Thus, the hair has a pleasing appearance after the manner of a true Marcel wave.

10 The members 10 and 11 must be secured in nested relation to impart the wave; and in such a manner that they may be adjusted longitudinally of each other. Further, they must be separable to permit insertion and removal of the hair 12. For this purpose, the members 10 and 11 are hingedly joined at one end by a slot and pin connection formed by the slots 24 in ears or extensions 33 on the outside walls of the member 11, and the pins 25 formed on the outer walls of the member 10. To maintain the members 10 and 11 in proper operating relationship, the pins 25 are provided with heads 26 which have a diameter slightly in excess of the width of the slot 24.

15 In assembling the members 10 and 11, force is applied to the corrugations at the end of the inner member 10 adjacent the pins 25 to compress the corrugations and reduce the width of the member. Or force may be applied to the end of the member 11 which carries slots 24 to increase the width of the member, such relative change in the width of the members being sufficient to allow the slots 24 to be placed on the heads 26. Appropriate force is then applied to force the heads 26 through the slots 24, the resilience of the parts being such that they immediately return to their initial configuration upon release of such pressure with the pins 25 in the slots 24.

20 The hinge formed by the slots 24 and the pins 25 permits the members 10 and 11 to be swung apart for insertion and removal of the hair.

25 To clamp the members together, the member 11 is provided at its other end with a centrally disposed slot 27 adapted to be engaged by a headed pin 28 on the member 10. The head of

the pin 28 is slightly wider than the slot 27 so that a small amount of force is necessary to force it through the slot 27 in either direction. The arrangement is such that when the members 10 and 11 are forced together, the slot 27 snaps over the pin 28 and is secured thereby in the position of Figure 2. Pressure in the opposite direction will force the slot 27 over the pin 28 to free the members and allow them to be swung apart. The height of the pin 28 under its head is somewhat less than that of the adjacent teeth 21 whereby a portion of the member 11 adjacent the pin is sprung down, the resulting friction between the head of the pin and the member 11 being such as to permit the desired longitudinal adjustment between the members, but to retain them in adjusted position against accidental movement. The slots 24 and 27 are elongated to permit the required longitudinal movement between the members 10 and 11.

In using the device it may be desirable to moisten the hair with an appropriate lotion or "wave set." To hasten the drying thereof as well as to promote the comfort of the user, ventilating apertures 30 are provided in the walls of both the members 10 and 11. It is contemplated that the teeth 21 and 22 be formed as by being struck from the material forming the respective members 10 or 11. Thus, apertures 31 and 32 are formed which assist in the ventilation. This effect may be heightened by striking the teeth in opposite directions so that the apertures are staggered as indicated in Figure 3.

In order to insure that a portion of the hair is free immediately adjacent the head and between the head and the first row of teeth to permit longitudinal adjustment of the lower member 10 on the head, the lower member 10 has a straight extension or lip 35 at its outer end in advance of the first row of teeth (see Figure 4).

The device is used in the following manner. The members 10 and 11 are swung apart and the member 10 is then placed in a suitable position on the head, the strands 12 of the hair to be waved having first been pulled forwardly. This hair is then swung upwardly and backwardly onto the member 10 and the member 11 is closed against the member 10, and clamped by passing the slot 27 over the head of the pin 28, the hair being confined between the members. That portion of the inner member 10 between the ears 33 of the outer member 11 is then grasped by the fingers of one hand, a tab or extension 34 on the member 11 being grasped by the fingers of the other hand. The members are then moved longitudinally with respect to each other causing the teeth 21 and 22 to move the hair in opposite directions and imparting a horizontal wave, as clearly shown in Figure 1. It is to be noted that the teeth 21 and 22 are respectively in contact with the cooperating member at all times, and thus there is no danger of the scalp being injured or irritated by contact with them.

I claim:

1. A hair waving device comprising a pair of nested arcuate combs, said combs having rows of generally radial teeth for supporting said combs in spaced relation to each other.

2. A hair waving device comprising a pair of nested arcuate members, said members having a plurality of spaced longitudinally extending rows of radial teeth for maintaining said members in spaced relation.

3. A hair waving device comprising a pair of

arcuate members, each member having alternate ridges and valleys extending generally longitudinally thereon, said members being adapted to nest with the ridges of one member in the valleys 5 of the other member, means forming comb-like teeth in said ridges and in said valleys for maintaining said members apart when nested to define a space for receiving the hair to be waved, and means for releasably maintaining said members 10 in nested relationship.

4. A hair waving device comprising a pair of arcuate members, each member having alternate ridges and valleys extending generally longitudinally thereon, said members being adapted to 15 nest with the ridges of one member in the valleys of the other member, means forming comb-like teeth in said ridges and in said valleys for maintaining said members apart when nested to define a space for receiving the hair to be waved, and 20 means for releasably maintaining said members in nested relationship, there being ventilating openings through said members.

5. A hair waving device comprising a pair of arcuate members, each member having alternate 25 ridges and valleys extending generally longitudinally thereon, said members being adapted to nest with the ridges of one member in the valleys of the other member, means forming comb-like teeth in said ridges and in said valleys for maintaining said members apart when nested to define 30 a space for receiving the hair to be waved, means pivotally joining said members at one end and allowing said members to be swung apart to facilitate insertion of the hair, and means forming 35 a clamp at the opposite end of the members for securing said members in nested relation.

6. A hair waving device comprising a pair of arcuate members, each member having alternate ridges and valleys extending generally longitudinally 40 thereon, said members being adapted to nest with the ridges of one member in the valleys of the other member, means forming comb-like teeth in said ridges and in said valleys for maintaining said members apart when nested to define 45 a space for receiving the hair to be waved, means forming a slot and pin connection between said members adjacent one end thereof for allowing said members to be swung apart to receive the hair, as well as to permit 50 adjustment between the members in the direction of the ridges, and clamping means adjacent the opposite end of the members for securing them in nested relation in adjusted longitudinal position.

7. A hair waving device comprising a pair of members, each member having alternate ridges and valleys, said members being adapted for assembly with the hair to be waved interposed between them, the ridges of one member being in 60 the valleys of the other and serving to wave the hair in one direction, said members having projecting comb-like teeth between which the hair is passed, and means for adjusting the relative longitudinal positions of said members for causing 65 said teeth to wave the hair in another direction.

8. A hair waving device comprising a pair of relatively longitudinally adjustable members adapted to receive the hair to be waved between them, said members respectively having alternate spaced rows of comb-like teeth between the members, the rows extending in the direction of 70 adjustment, the teeth on each of said members cooperating with the other member to define adjacent closed passages for confining the hair, 75

whereby relative adjustment of the members waves the hair.

9. A hair waving device comprising a pair of inner and outer arcuate members for use on top of the head, said members having nesting ridges and valleys as well as cooperating teeth for imparting a Marcel wave to hair confined between the members, said inner member having an extension from the first valley for receiving the hair without waving it, whereby the hair confined between the members is left with a straight portion between the head and the wave.

10. A hair waving device comprising a pair of relatively longitudinally adjustable members adapted to receive the hair to be waved between them, said members respectively having alternate

5 spaced rows of comb-like teeth between the members, the rows extending in the direction of adjustment, the teeth on each of said members cooperating with the other member to define adjacent closed passages for confining the hair, whereby relative adjustment of the members waves the hair, means forming a slot and pin connection between said members adjacent one end thereof for allowing said members to be 10 swung apart to receive the hair as well as to permit longitudinal adjustment between the members, and means adjacent the opposite end of said members for securing them in nested relation and maintaining them in adjusted longitudinal position.
